TOY CANNON.

1,244,876.

Specification of Letters Patent. Patented Oct. 30, 1917.

Application filed May 31, 1917. Serial No. 171,956.

To all whom it may concern:

Be it known that I, WALTER O. McDANIEL, a citizen of the United States, residing at St. Louis, Missouri, have invented a certain 5 new and useful Improvement in Toy Cannons, of which the following is a full, clear, and exact description, such as will enable others skilled in the art to which it appertains to make and use the same.

10 This invention relates to toy cannons of the type that comprise a spring for shooting or projecting an object from the barrel of the cannon.

One object of my invention is to provide a 15 toy cannon of the type referred to, which is so constructed that the barrel of same can be tilted vertically and also swung horizontally with relation to the base portion on which the barrel is mounted, thereby producing a toy cannon whose general appearance and principle of operation, so far as the adjustment of the barrel is concerned, resembles a real cannon.

Another object is to provide a toy cannon 25 of the type referred to, in which the means employed for storing up energy in the spring consists of a manually-operable device arranged on the underside of the barrel and adapted to be moved longitudinally of 30 the barrel by a simple operation of the hand of the child using the cannon.

And still another object is to provide a toy cannon of simple construction that can be manufactured at a low cost and stored 35 compactly when it is not in use, or when it is in transit from the manufacturer to the place where it is to be sold. Other objects and desirable features of my invention will be hereinafter pointed out.

40 Figure 1 of the drawings is a side elevational view of a toy cannon constructed in accordance with my invention.

Fig. 2 is a longitudinal sectional view of same.

45 Figs. 3 and 4 are vertical transverse sectional views, taken on the lines 3-3 and 4-4, respectively, of Fig. 2.

Fig. 5 is a horizontal sectional view, taken on the line 5-5 of Fig. 2; and

50 Fig. 6 is a detail sectional view, illustrating a slight modification of my invention.

Referring to the drawings, which illustrate the preferred form of my invention, A designates the barrel of the cannon which 55 consists of a relatively long member of substantially cylindrical shape whose front end

portion 1 tapers slightly and merges into a flared rim 2 at the mouth of the barrel. Said barrel is mounted on a base or supporting structure in such a manner that it 60 can be tilted vertically, both upwardly and downwardly, and also swung horizontally. In the form of my invention herein shown the supporting structure just referred to comprises a base plate 3 carried by legs 4 65 and a turntable 5 rotatably mounted on said base plate and having the barrel A pivotally connected thereto in such a manner that said barrel can be tilted upwardly and downwardly. It is immaterial how the barrel 70 is pivotally connected to the turntable 5, but I prefer to provide said turntable with an upwardly-projecting ear 6 that is pivotally connected by means of a horizontally-disposed pivot pin 7 to an ear 8 that projects 75 downwardly from a saddle plate 9 arranged on the underside of the barrel A adjacent the rear end of same, said saddle plate being connected to said barrel in any desired manner. The turntable 5 and base plate 3 80 preferably consist of substantially cup-shaped castings of the same general form and dimensions arranged so that the edges of the flanges on same will contact with each other, said elements being secured together 85 by a fastening device 10, preferably a rivet that passes vertically through said elements, as shown in Figs. 2 and 3, the turntable being held in vertical alinement with the base plate by lugs 10^a on the inner side of one of 90 said parts that lap over the flange or annular side wall portion of the other part. The legs 4 can either be integrally connected with the base plate 3 or detachably connected to same, it being preferable to 95 detachably connect the legs to the base plate so as to enable the supporting structure to be taken apart when the cannon is not in use, or when it is being shipped from the manufacturer to the place where it is to be 100 sold. In the cannon herein shown the legs 4 are provided at their upper ends with reduced extensions 4^a that pass upwardly through holes in lugs 11 that project radially from the base plate 3, each of said 105 lugs having a set screw 12 mounted therein so as to engage the extension 4^a on the leg with which it co-operates, and thus securely lock said leg to the base plate. Each leg 4 is also preferably provided at its upper end 110 with a relatively wide shoulder 4^b that bears against the underside of its co-operating lug

11. The horizontal pivot pin 7 previously referred to that pivotally connects the barrel of the cannon to the turntable 5 preferably consists of a bolt provided with a wing 5 nut 7^a which can be turned so as to securely clamp the ears 6 and 8 together, or which can be removed from the bolt, in case it is desired to disconnect the turntable from the saddle plate 9.

10. The barrel A is provided with a center bore α in which a compression spring 13 and plunger 14 are arranged, as shown in Fig. 2, said spring being positioned between the plunger 14 and an abutment or plug 15 that 15 serves as a closure for the rear end of the bore α in the barrel A. The means employed for compressing the spring 13 or placing it under tension is of novel construction and consists of a manually-operable member B 20 slidingly mounted on a guide rod 16 arranged on the underside of the barrel A and provided with an upwardly-projecting finger 17 that is positioned in front of a trigger 18 that projects downwardly from the 25 plunger 14, as shown in Fig. 2; the barrel A being provided on its underside with an elongated slot y in which the finger 17 and trigger 18 travel. When the member B is moved rearwardly, the finger 17 thereon 30 engages the trigger 18 on the plunger and moves the plunger rearwardly, thereby compressing the spring 13 or placing it under tension. When the plunger reaches a certain position, the trigger 18 thereon snaps 35 into engagement with a spring 19, thereby causing the plunger to be locked, and consequently, holding the spring 13 under compression. Various means may be used for locking the plunger 14, but I prefer to use 40 a leaf spring that is arranged in a groove on the underside of the barrel A and which is provided at its front end with an upwardly curved portion 19^a in which a hole 20 is formed, so as to receive the trigger 18, 45 the rear end of said spring being securely connected to the barrel A in any suitable manner. When the member B is moved rearwardly to compress the spring 13, the trigger 18 on the plunger engages the curved 50 portion on the front end of the spring 19 and depresses said spring sufficiently to permit the trigger to snap into the hole 20 in the spring. As soon as the operator releases the member B, said member will be moved 55 forwardly into the position shown in Fig. 2 by means of a coiled compression spring 21 that is arranged between the rear end of said member and the upturned portion at the rear end of the guide 16 on which the 60 member B is slidingly mounted.

After the spring 13 has been placed under tension, the object or projectile to be fired by the cannon is introduced into the bore α in the barrel A at a point in front of the 65 plunger 14. Thereafter, the spring 19 is

depressed so as to release the trigger 18 and permit the spring 13 to expand by means of a trigger-releasing mechanism that consists of a horizontally-disposed rock shaft 22 journaled in the saddle plate 9, as shown in Fig. 5, and provided with a crank arm or offset portion 23 that engages the spring 19 and moves the free end of same downwardly out of engagement with the trigger 18, when said shaft is rocked in one direction by means of a handle 24 on one end of the shaft.

The object or projectile used with the cannon may be of any preferred shape, so long as it is of such form that it will pass freely through the bore α in the barrel, and said object can be introduced into the mouth of the barrel and moved rearwardly through the bore α into a position in front of the plunger 14, or said object can be introduced into the bore α through an opening in the barrel A that leads laterally from the bore and terminates in the outer surface of the barrel A. I prefer to construct the cannon in such a manner that the object or projectile α that is to be shot can be introduced into the barrel A at a point adjacent the rear end of same, and to this end I have provided the barrel A with a slot 25, shown in Fig. 2, that leads laterally from the bore α and terminates in the outer surface of the upper side of the barrel A. The slot or opening 25 in the barrel is normally closed by a cover plate 26 which can be secured to the barrel in any desired manner, the cover plate 26 herein shown being pivotally connected to the barrel by means of a pivot pin 27 that passes through the rear end portion of said plate. If desired, the cover plate 26 can be provided with an upwardly-projecting part 28 that serves as a sight and also as a handle by which the plate can be moved into and out of operative position.

In practice I prefer to form the barrel A from wood and most of the other elements from cast metal, so as to enable the cannon to be manufactured and sold at a low cost. In the form of my invention herein shown the legs 4, base 3, and turntable 5 consist of castings, and the saddle plate 9 also consists of a casting which can be connected by means of screws or other suitable fastening devices 9^a to the wooden barrel A. The spring compressing member B can be formed conveniently from wood and the guide 16 on which said member is slidingly mounted can be formed conveniently from a small rod or round bar provided at its rear end with an upturned portion that is riveted to the saddle plate, as shown in Fig. 2, and provided at its front end with an upturned portion that is riveted to a plate 16^a connected by suitable fastening devices to the barrel A.

Instead of providing the barrel A with a

permanent abutment 15 against which the rear end of the spring 13 bears, as shown in Fig. 2, the barrel can be provided with a movable abutment 15^a, as shown in Fig. 6, 5 that can be adjusted by means of a screw 15^b, so as to vary the tension of the spring 13 when it is under compression, said screw 15^b being mounted in a plate 15^c that serves as a closure for the rear end of the bore *x* in 10 the barrel A.

A toy cannon of the construction above described looks similar to a real cannon, and the barrel of same can be tilted vertically and swung horizontally in substantially the 15 same manner as the barrel of a real cannon in getting the range of the object being shot at.

And still another desirable feature of such a cannon is that the spring can be placed 20 under compression by a simple operation of one hand of the child using the cannon, this, of course, being due to the fact that the spring compressing member B is slidably mounted on a guide 16 arranged on the underside of the barrel of the cannon. The lateral opening or side opening in the barrel through which the projectile is introduced 25 into the bore of the cannon enables the cannon to be loaded in a manner somewhat similar to the way a real cannon is loaded. The frictional contact between the turntable 5 and the base 3 on which it rests is sufficient to hold the turntable in the position into 30 which it has been turned, and the wing nut and bolt that secure the saddle plate to the turntable permit the coöperating ears on 35 said parts to be clamped so securely together that the barrel will remain either in a horizontal position or in an inclined position.

40 A cannon of the construction above described can be manufactured at a low cost, and as the barrel is detachably connected to a supporting structure which can be taken apart easily, it is possible to pack the cannon in a small box, when it is in transit from the manufacturer, or when it is not in use.

Having thus described my invention, what I claim, and desire to secure by Letters Patent, is:

50 1. A toy cannon, comprising a supporting structure provided with a base that consists of a substantially cup-shaped casting, a turntable that consists of a substantially cup-shaped casting arranged so that the edge of 55 the side wall portion of same will bear upon the side wall portion of the base, and a barrel connected to said turntable by a horizontal pivot.

2. A toy cannon, comprising a base and 60 turntable formed by oppositely-disposed, cup-shaped castings, a vertical pivot pin that connects said parts together, lugs on the inside of one casting that lap over the side wall portion of the other casting, and a barrel carried by said turntable.

3. A toy cannon, comprising a barrel provided with a longitudinal bore, a spring and plunger arranged in said bore, said plunger being provided with a trigger, a member that is adapted to be moved longitudinally 70 of the barrel for placing said spring under compression, a flat spring provided with a hole that cooperates with the trigger on said plunger to hold the spring under compression, and means for actuating said spring so 75 as to release the plunger and permit the spring to expand.

4. A toy cannon, comprising a barrel provided with a longitudinal bore, a spring and plunger arranged in said bore, a trigger on 80 said plunger that projects into an elongated slot in the barrel, a member that is adapted to be moved longitudinally of the barrel to exert pressure on said plunger in a direction to compress said spring, a resilient device 85 provided with an opening into which the trigger on said plunger snaps after the spring has been placed under compression, and a rock shaft arranged transversely of the barrel and provided with a portion that 90 engages said resilient device and moves it out of engagement with said trigger when said shaft is rocked in one direction.

5. A toy cannon, comprising a barrel provided with a longitudinal bore, a spring and a plunger arranged in said bore, a trigger on 95 said plunger that projects into an elongated slot in the barrel, a member slidably mounted on a guide that extends longitudinally of the barrel that is adapted to engage said trigger when said member is moved in a direction to place said spring under compression, a flat spring provided with a hole that cooperates with said trigger to hold the spring under compression, and a lateral opening in said barrel through 100 which the projectile or object to be fired can be introduced into the bore in the barrel.

6. A toy cannon, comprising a supporting structure provided with a turntable, a saddle plate connected to said turntable by a horizontal pivot, a barrel secured to said saddle plate and provided with a longitudinal bore, a spring and a plunger arranged in said bore, a trigger on said plunger that 110 projects into an elongated slot in said barrel, a guide rod arranged longitudinally of the barrel and connected at its front end to the barrel and at its rear end to said saddle plate, and a member slidably mounted on 115 said guide rod and having a portion that projects into the slot in the barrel at a point in advance of said trigger.

7. A toy cannon, comprising a supporting structure provided with a turntable, a saddle plate connected to said turntable by a horizontal pivot, a barrel secured to said saddle plate and provided with a longitudinal bore, a spring and a plunger arranged in said bore, a trigger on said plunger that 125

projects into an elongated slot in said barrel, a guide rod arranged longitudinally of the barrel and connected at its front end to the barrel and at its rear end to said saddle plate, a member slidably mounted on said guide rod and having a portion that projects into the slot in the barrel at a point in advance of said trigger, a spring on said guide rod that exerts pressure on said member so as to normally hold it in a certain position, a resilient element provided with a hole into which the trigger on the plunger snaps after the spring has been placed under compression, and an operating shaft arranged transversely of the barrel and provided with a portion that engages said resilient element and disconnects it from said trigger.

8. A toy cannon, comprising a supporting structure composed of a base and legs detachably connected to said base, a turntable 20 on said supporting structure, a barrel pivotally connected to said turntable and provided with a longitudinal bore, a spring and a plunger in said bore, means arranged to move longitudinally of the barrel for compressing said spring, a resilient element for holding said spring under compression, means for tripping said element so as to release the spring, and a lateral opening in the barrel through which the projectile or object to be fired can be introduced into the bore in the barrel. 25 30
